(57) **CLAIM**

The ornamental design for a bipolar electrode, as shown and described.

DESCRIPTION

FIG. 1 is a front top and right side view of a bipolar electrode according to the present invention.

FIG. 2 is an enlarged front view of the bipolar electrode of FIG. 1.

FIG. 3 is an enlarged rear view of the bipolar electrode of FIG. 1.

FIG. 4 is a left side view of the bipolar electrode of FIG. 1.

FIG. 5 is a right side view of the bipolar electrode of FIG. 1.

FIG. 6 is a top view of the bipolar electrode of FIG. 1; and, FIG. 7 is a bottom view of the bipolar electrode of FIG. 1. The dashed lines illustrate environment that does not form a part of the present invention, and no claim is made to the material illustrated with dashed lines.

1 Claim, 7 Drawing Sheets
